PORTRABLE PULPIT

Robert C. Adams and Irma O. Adams, Escondido, Calif.

Application July 29, 1955, Serial No. 37,208

Term of patent 14 years

(Cl. D33—7)

Fig. 1 is a perspective view of a portable pulpit showing our new design, with the pulpit illustrated in position for use;

Fig. 2 is a perspective view thereof in position for carrying;

Fig. 3 is a top plan view of the portable pulpit;
Fig. 4 is an elevational view of the open side thereof;
Fig. 5 is a bottom plan view of the portable pulpit;
Fig. 6 is an elevational view of the closed side thereof;
and

Fig. 7 is an end elevational view of the portable pulpit as shown in Fig. 2.

We claim:

The ornamental design for a portable pulpit, substantially as shown.
